UNITED STATES PATENT OFFICE

ALLAN S. RICHARDSON, OF BUTTE, MONTANA

METHOD AND APPARATUS FOR COOLING MINE AIR

Application filed November 23, 1931. Serial No. 576,857.

This invention relates to a method and apparatus for conditioning mine air and particularly to a method and apparatus by which the air may be cooled by heat exchange effected in proximity to the place or places in the mine workings where cooling is desired.

Heretofore, the air in mines has been cooled by forcing cooled air through the mine, but this method is impractical where the workings to be cooled are so far removed from the entrance to the mine that the air becomes heated before reaching the workings. The present invention contemplates cooling the air at the place or places in the interior of the mine where cooling is desired by means of heat exchange apparatus disposed at these places.

The use of a conventional refrigerating system in a mine is not generally practical due to the hazard attendant upon the use of the usual refrigerant mediums and the cost of operating a refrigerating system in the interior of a mine. According to the present invention, an air cooling system, for example, of the type employing spray coolers, is disposed at or near the workings to be cooled and the refrigerant medium employed by this system is cooled through heat exchange with a second system which has a cooling means located exteriorly of the mine.

In a specific embodiment, the invention may be practised with certain desirable results by carrying out, in a single step, the cooling of the air by the primary refrigerant medium and the cooling of the primary refrigerant medium by the second refrigerant medium.

An object of the present invention is to provide a method and apparatus for conditioning mine air which is safe and inexpensive to operate.

Another object of the invention is the provision of apparatus for cooling mine air, which apparatus is particularly adapted for use in localities where the temperature of the surface air attains values below zero degrees Fahrenheit.

Other objects of the invention will appear from the appended specification taken in con-

nection with the accompanying drawings showing one form of the invention.

In the drawings:

Fig. 1 is a somewhat diagrammatic view showing the portion of the apparatus which is located at the mine entrance.

Fig. 2 is a diagrammatic, plan view partially in cross-section, showing the portion of the apparatus which is located in proximity to the workings to be cooled.

Fig. 3 is a somewhat diagrammatic view, similar to Fig. 2, showing another modification of the invention, and

Fig. 4 is a diagrammatic, side elevational view, partially in cross-section, showing the device according to Fig. 3.

A cooling tower 1 of the air-cooled type is disposed adjacent the mine entrance and is connected, by means of pipes 2, 3 extending into the mine, with a heat exchanger 4 of the two-fluid type which is disposed in a recess in proximity to the working to be cooled. A centrifugal pump 5 is provided for circulating a refrigerant medium, such as calcium chloride brine, between the heat exchanger 4 and the cooling tower 1. Owing to the fact that the brine which has been warmed in the heat exchanger 4 has a lower specific gravity than that which has been cooled in the cooling tower 1, the convection effect is nearly sufficient to effect circulation of the brine and only a small amount of power need be applied to the pump 5 to maintain the circulation of the brine.

Disposed in the path of flow of the mine air, which may be circulated by blowers (not shown) if circulation due to convection is not possible, is a spray cooler 6 which is connected to the heat exchanger 4. The spray cooler 6 comprises four sections 7 and 7' through 90 which a cooling liquid, preferably water, is circulated, in a direction opposite to the direction of flow of the air. Each section comprises a header 8 from which depends a plurality of vertical nozzles 9 arranged to spray water into the air stream and a baffle 10 at the downstream side of the nozzles 8 to prevent the water from being carried along by the air stream.

The intermediate sections 7 are provided

with three times as many nozzles 9 as the outer section 7', hence the circulation of the water through the sections is accomplished by recirculating through the intermediate sections 7 5 two thirds of the water which has been expelled from the nozzles 9. Pumps 11 are provided between each section of the spray cooler 6 and between the spray cooler 6 and the heat exchanger 4 for circulating the water.

10 The operation of the system is as follows:

15 The mine air is drawn through the spray cooler 6 and heat is taken up by the water which is circulated through the heat exchanger 4 where heat is transferred from the water to the brine. The brine is circulated through the cooling tower 1 where heat is removed by a stream of atmospheric air which is drawn through the cooling tower 1.

20 In Figs. 3 and 4 is shown a second embodiment of the invention. Disposed in the workings is a cooling chamber 12 having at one end a blower 13 for drawing the air to be cooled from the nearby workings, forcing the air through the cooling chamber 12 and returning 25 the air to the workings.

25 Arranged in the path of air through the chamber 12 are a plurality of sets of cooling coils 14, 14' connected in series and connected by pipes 15, 16 to a cooling tower (not shown) 30 similar to the tower 1 of Fig. 1 and disposed preferably at or near the entrance to the mine. A refrigerant is circulated through the sets of cooling coils 14, 14' in a direction counter to the direction of flow of air through the chamber 12.

35 Adjacent each set of cooling coils 14 and positioned to spray water or other liquid medium thereon, is a set of sprayers 17, 17' to each set of which is connected a pump 18 which in turn is connected to a sump 19 lying under the set of sprayers 17. The pump 18 draws water from the sump 19 and forces it from the sprayers 17 in the form of a curtain through which the air must pass in traveling 45 through the chamber 12. On the downstream side of each set of coils is disposed a set of baffles which prevent the water from being carried along by the air stream.

40 The operation of this form of the invention is as follows:

50 Mine air is drawn from the workings and is forced through the chamber 12 by the blower 13 where heat is transferred to the curtain of water and from the curtain of water 55 to the refrigerant medium in the cooling coils 14, 14'; heat is also transferred directly from the air to the coils 14, 14'. The heated refrigerant is then conducted through pipe 16 to the cooling tower as in the first form of the 60 invention and the heat removed in a known manner and the refrigerant returned to the coils 14, 14' through pipe 15.

65 The use of a cooling medium such as calcium chloride brine has the advantages that the relatively high specific heat of the brine

70 effects the rapid removal of a large amount of heat with the expenditure of but little power and also the low freezing point of the brine permits the use of the apparatus in localities where the surface temperature often falls considerably below zero degrees Fahrenheit.

75 Among the advantages derived from the use of water, instead of any other cooling medium, in the open system may be mentioned, elimination of the possibility of explosions, absence of the presence of noxious gases in the workings, and economy in the cost of renewal of the cooling medium. In view of the fact that the cooling system which 80 includes the cooling tower, is a closed system, any cooling medium having the desired characteristics may be used inasmuch as none of the hazards encountered in the use of an open system will be met.

85 A further advantage of the present system is that the portion of the system wherein there is a large pressure head on the refrigerant medium is constituted by a completely closed circuit. This arrangement has the advantage that the head on one side of the system balances the head on the other side of the system, whereby only a very small amount of power is necessary to effect circulation of the refrigerant medium, the power required 90 being only that which is necessary to overcome friction of the refrigerant medium. Moreover, the circulation is still further assisted by the convection of the refrigerant medium.

95 A further advantage is derived in that an efficient washing of the air is obtained which is of considerable importance in the conditioning of mine air. It is desirable to effect a very complete cleaning of the air in order 100 to eliminate the deleterious effect upon the health of the miners, caused by the extremely fine particles of matter suspended in the air and also to eliminate the possibility of dust explosions.

110 I claim:

115 1. The method of conditioning mine air which comprises, contacting the air with water at the workings, circulating said water in heat exchange relation with a second cooling medium having a freezing point substantially lower than that of water to transfer heat from said water to said second cooling medium, circulating said second cooling medium in a closed circuit, and removing heat from said second cooling medium at a point remote from the workings.

120 2. The invention as set forth in claim 1, wherein said heat transfer is carried out in the presence of the air which is being conditioned.

125 3. Apparatus for conditioning mine air comprising, an air cooling and washing chamber disposed at the workings, means for circulating a liquid cooling medium compris-

ing water through said chamber in direct contact with the air to be conditioned, a closed refrigerant circuit containing a refrigerant medium having a freezing point 5 substantially lower than that of water, means disposed substantially at the surface for cooling said refrigerant medium, and heat exchange means in the vicinity of said workings for transferring heat from said water 10 to said refrigerant medium.

4. The invention as set forth in claim 3, wherein said heat exchange means is disposed in said chamber.

5. Apparatus for conditioning mine air 15 comprising, a closed refrigerant circulating system containing a refrigerant medium and including a plurality of serially connected cooling coils disposed in said workings for circulating said refrigerant medium in counter-current relation with the air to be cooled, means for forcing said air past said coil, means at a point remote from said workings for cooling said refrigerant medium, and means including a separate, closed circuit for 20 each of said coils for circulating a second refrigerant in contact with said air and said coils simultaneously.

6. Apparatus for cooling mine air comprising, a series of chambers disposed in the 25 mine workings, means for forcing the air to be cooled through said chambers, a plurality of serially connected coils disposed one in each chamber, means in each chamber for circulating through the chamber a refrigerant medium in simultaneous contact with the air to be cooled and the coil, means for circulating a second refrigerant medium in a closed circuit through said coils in counter-current relation to the air to be cooled, and 30 means remote from said workings for cooling said second refrigerant.

In testimony whereof, I affix my signature.
ALLAN S. RICHARDSON.
